UNITED STATES PATENT OFFICE.

OSCAR SCHWIMMER, OF LOS ANGELES, CALIFORNIA, ASSIGNOR, BY MESNE ASSIGNMENTS, TO PATENT PRODUCTS COMPANY, A CORPORATION OF CALIFORNIA.

AUTO SIGNAL.

Application filed January 10, 1919, Serial No. 270,600. Renewed March 28, 1922. Serial No. 547,541.

To all whom it may concern:

Be it known that I, OSCAR SCHWIMMER, a citizen of the United States, residing at Los Angeles, county of Los Angeles, and 5 State of California, have invented a certain new and useful Improvement in Auto Signals, of which the following is a specification.

My invention relates to a means for indicating the direction of travel of automobiles, especially by night, and has particular reference to a device adapted for co-operation with the human hand in signalling following vehicles the intended movement of the forerunning machine.

One of the objects of this invention is to supplant the unsatisfactory mechanical contrivances appurtenant to a car for signalling, with an efficient, simple and unfailing means, in which the human hand performs the act of indication while the invention herein described itself furnishes the illumination and the danger signal, whereby when the hand is extended to indicate the direction of travel, the signal may be plainly visible by following machines, while the hand is brightly illuminated.

Another object of the invention is to provide a means of illumination for and entirely controllable by the hand, which means may be conveniently, easily and firmly grasped and held by the fingers.

In illustration of a form of embodiment of the invention is the accompanying drawing, wherein,

Fig. 1 is a sectional view.

Fig. 2 is a fragmentary view of a steering wheel of an automobile of temporary attachment of the invention, and

Fig. 3 is a view illustrative of the manner of use.

With especial reference to the drawing, the invention may comprise a body 1, formed with a reflector 2, and with a base 3, united with the reflector 2 by a reduced portion 4, shaped, constructed, designed and arranged for accommodation to and prehension by the fingers or other members.

The reflector 2, is provided with a translucent lens or plate 5, preferably of a color indicative of danger, and which may be removably fitted over the end of the reflector

by mounting the lens or plate in an annular ring 5' and frictionally applying same.

The reflector is provided with a plurality 55 of holes or openings 3^a through which the rays of white light from the lamp may stream for illuminating the hand, which thus becomes visible from a considerable distance and in combination with the danger 60 light, effectively warns autoists of the intention of the user.

Within the reflector, is an electric globe 6, threading in a socket 7, contained in a body of insulating material 8 which is provided with a plurality of passageways 9 and 10, through which extend the respective wires 11 and 12. The wire 11 is connected at one end to the socket 7, and at the other end to a contact plate 13, fastened 65 on the bottom of a disk or plate 13' of insulating material fitted in the base 3.

The wire 12, is connected at one end to the lamp 6, extends through an orifice 14 in the base 3 and may be connected at its 70 other end with a plug 15, adapted for insertion in a suitable socket, not shown, which supplies the source of electrical energy.

Another wire 16, leads from the plug 15 and is connected to a resilient contact plate 80 17, operable by a button 18, to establish contact thereof with the contact plate 13, and complete the circuit.

This button 18 is mounted in a plug 19, having threading engagement with the base 85 3, and lies within convenient reach of the thumb or other member, when the device is grasped for use.

Obviously, the wires 12 and 16 may be of any length desired, for enabling the arm 90 and hand with the signal to be extended.

In operation, the reduced portion 4, is grasped by and between preferably the second and third fingers, with the base 3 inside the hand, whereby the button 18, may be readily operated by the thumb. On pressure of the button, the lamp in the reflector is lighted and becomes plainly visible through the translucent plate 5, which indicates danger to the following machines, 100 while at the same time the hand is brilliantly illuminated.

In Fig. 2 I have shown a means for conveniently attaching the signal to an auto-

mobile, consisting of a plate 20, having spring arms 21 formed to hold the signal elevated and the button free of contact with the plate.

5. What I claim, is:—

1. A signalling device involving the use of the human hand comprising a body adapted to be held between the fingers and provided with a source of illumination for 10 the hand.

2. A portable signalling device involving the use of the human hand comprising a case having a stem adapted to be held between the fingers, a source of light within 15 the case, said case having openings for passage of light rays laterally so as to illuminate the hand.

3. A portable signalling device involving the use of the human hand comprising a case having a stem adapted to be held between the fingers, a source of light disposed 20 within said case, said case having a lens to direct light away from the hand and openings for passage of light rays laterally 25 so as to illuminate the hand.

4. A signalling device involving the use of the human hand comprising a body adapted to be held between the fingers and

provided with openings, a translucent disk on said body, and a source of light within 30 said body to illuminate the hand and simultaneously indicate danger.

5. A signalling device involving the use of the human hand comprising a body formed with a reduced portion adapted to 35 be held by and between the fingers and provided with openings, and with a translucent disk, a source of light within said body to illuminate the hand through the openings therein, and simultaneously indicate 40 danger, and means to control the illumination.

6. A signalling device comprising a reflector provided with a lamp and with means for prehension by the fingers, and 45 having openings for illuminating the hand, a disk of translucent material on said reflector, an electrical circuit including the lamp and a switch, and means for controlling the switch.

50 In testimony whereof I have set my hand in the presence of two witnesses:

OSCAR SCHWIMMER.
